York, N. Y., a corporation of Delaware

Application March 17, 1931. Serial No. 523,270

41 Claims. (Cl. 175—183)

This invention relates to a stroboscope. Among the objects of this invention is the provision of improved mechanism for measuring the length of an electrical pulse, for measuring the time required for a relay to close and open its contact, for obtaining a still view of moving objects, for obtaining a slow movement view of moving objects, for observing an object at any point in its movement, and for visually indicating on a graph of the pulse operating said object the point at which such object is viewed.

Other objects will be apparent from the following description taken in connection with the drawings, in which

Fig. 1 is a front view of the stroboscope showing a suitable control board;

Fig. 2 is a top plan view of the stroboscope;

Fig. 3 is a vertical section on the line 3—3 20 of Fig. 2;

Fig. 4 is a vertical section on the line 4—4 of Fig. 2 with parts broken away;

Fig. 5 is a vertical section on the line 5—5 of Fig. 2;

Fig. 6 shows the wiring diagram;

Fig. 7 shows a computing chart;

Fig. 8 shows the graph of a pulse produced by an oscillograph;

Fig. 9 shows the slotted disk of the stroboscope;

Fig. 10 shows diagrammatically the neon tube used in combination with an oscillograph;

Fig. 11 shows a wiring diagram for testing the length of a pulse and for testing the time required for a relay contact to close and to open;

Fig. 12 is a diagrammatic view showing the control of the dial stroboscope, the observation stroboscope, and the stroboscope in the oscillograph, by the eccentric cam shown in Figs. 2, 3 and 4; and

Fig. 13 is a side view of an indicator unit.

The mechanism shown in Figs. 1 to 5 includes a cabinet 1, enclosing various switch mechanisms controlled by manipulative means on a panel board 2. Mounted on top of the cabinet 1, shown in Fig. 2, is a motor Mo whose armature shaft may be connected by a coupling and flywheel to a shaft 3 which extends toward the left, Fig. 2, and has secured thereto a pair of eccentric disks 4, Figs. 4 and 5, on which is mounted a cylinder 5 constituting a pulsing cam. The shaft 3 is suitably supported on a bearing 6 mounted on top of the cabinet 1. Cooperating with the cylinder 5 are circuit closing contacts

55 a, b, c and d, Fig. 2. Each contact comprises

spring members 10 and 11, Fig. 5, secured to a block of insulating material 12 supported on the cabinet 1. The spring member 11 carries a block of insulating material 13 which cooperates with the cylinder 5. As the spring member 11, 60 during the rotation of cylinder 5, is permitted to move toward the shaft 3 it carries the spring contact carrying member 10 with it to disengage its contact from the contact on the stationary adjustable screw bolt or contact member 14 carried on a standard 15 secured to the cabinet 1, as shown at the right hand side of Fig. 5. As the cylinder moves the block 13 away from the shaft 3 the member 11 is moved to the left, as shown at the left side in Fig. 5, 70 permitting the contact member 10 to move to the left to engage the adjustable stationary contact 14 at the left hand side of Fig. 5. As the contact c is closed it connects battery connected to the spring contact member 10 across 75 the adjustable contact 14 and the standard 15 to a line leading to one of the pulse counting or continuous pulse producing mechanisms, as will appear more clearly in connection with the description of Fig. 6. As the members 10 and 11 assume the position shown at the right of Fig. 5 they open the circuit between battery and the pulse counting or continuous pulse producing mechanisms.

Two pairs of contacts a and c, and b and d 85 are preferably provided and one of these pairs may be used as a spare pair of contacts, or pulses may go out over both pairs at the same time to test two relays at the same time.

Well known mechanism may be provided to 90 control the speed of the motor to rotate the cylinder at any desired number of rotations per second to produce any desired or required number of pulses. The adjustable contact members 14 may be moved toward or away from the cylinder 5 to determine the length of the pulse from the battery over the contact members 14 and 10 for any given speed of the motor. A relay may be operated by the pulse produced by this mechanism, and by observing on a dial later referred 100 to minimum and maximum lengths of pulses at which the relay fails to function, and then taking the means between the minimum and maximum length of pulses the proper operating pulse for the relay may be determined.

As shown in Fig. 3, the shaft 3 is extended to the left, and at its left end carries a slotted disk 19, Figs. 3 and 9. The disk 19 is located within a housing 20 which constitutes a bearing for the shaft 3 and is provided with a foot 110

resting on the cabinet 1. The outer end of the housing 20 carries a graduated annular member 21 which preferably is provided with one hundred divisions, as shown in Fig. 1. The graduated member or dial 21 is provided with a set screw 22 which operates in a groove 23 in the housing 20 for permitting adjustment of the member 21 with respect to the housing for purposes later referred to, and for securing it in 10 adjusted position.

Secured to the shaft 3 is an eccentric member 24 which counterbalances the pulsing cylinder or cam 5. Surrounding the member 24 is a cylindrical member 25 mounted concentrically 15 with respect to the shaft 3 and secured to the disk 19. Coiled about the cylinder 25 and spaced therefrom and from the disk 19 and the housing 20 is a neon tube 26, as indicated in Fig. 3. The outside surface of the cylinder 25 and the 20 inside surface of the housing 20 are preferably coated with white paint to increase the illumination through the slit of the disk 19, as is obvious.

Supported on the right hand end of the housing 20, Fig. 3, is a worm gear 30 which is operated by worm 31 on a shaft 32 driven by a motor mo, Fig. 1. The motor is preferably controlled in any suitable manner to operate forwardly or reversely.

30 The shaft 32 may be provided with a flywheel 33, Fig. 1, by means of which the shaft 32 may be turned by hand for purposes later set forth. The worm gear 30 carries a pair of contact members 34 and 35, Figs. 2, 3 and 4. The contact 35 member 35 is provided with a block of insulating material 36 cooperating with the eccentrically mounted pulsing cylinder or cam 5. By means of the motor mo the switches 34 and 35 may be moved in a forward direction or in the 40 reverse direction with respect to the direction of the movement of the cylinder 5 so that the circuit made by the contact members 34 and 35 will bear a variable timed relation to the circuits made by the contact members 10 and 14, 45 Fig. 5. As shown in Fig. 3, the contact members 34 and 35 are provided with brushes cooperating with rings 36 and 37 carried by a block of insulating material secured to the housing 20. Cooperating with the rings 36 and 37 are brushes 50 connected to incoming and outgoing circuit leads.

The operation and function of the mechanism so far described may be made clear by reference to Fig. 6 which shows a wiring diagram for 55 this mechanism. In this diagram the pulsing cam driving motor is indicated by Mo and the motor switch is indicated by B which connects the terminals of the motor to the terminals of a 48 volt battery. Below the motor Mo are indicated the pulsing contacts *a*, *b* and *c*, *d*. The neon tube is indicated below the switches at 26. On the left of Fig. 1 is shown a pulse counting controlling dial 40 which operates a contact arm 41, Fig. 6, with which are associated ten fixed contacts 1 to 10. On the right in Fig. 1 is shown another pulse counting controlling dial 40r, the purpose of which will be brought out later.

70 The function of the pulse counting controlling dials 40 and 40r is to control the number of pulses sent out of the mechanism to a relay or relays to be tested. The arm 41 or 41r in contact with the contacts 1 to 10 controls the transmission of one to ten pulses by stopping the transmission after one to ten pulses have been

sent out. The circuits over arms 41 and 41r are completed by contact arms 42 and 42r operated by stepping magnets SM and SMr.

The various manipulative means for controlling the mechanism shown in Fig. 6, are shown 80 in Fig. 1. The motor is set in operation by throwing the switch B which, as shown in Fig. 1, completes the circuit through the motor Mo over lines 45 and 46. As the motor is operated the pulsing cam 5 causes the various contacts *a*, 85 *b*, *c* and *d* to close once during each rotation of the cylinder 5. As the contact *b* is closed it extends minus on the line 46 to the line 47 which extends to the upper contact of the switch SC which in one position, as indicated, 90 controls the transmission of series of impulses and in the other position controls the transmission of continuous impulses. The line 47 also extends to the contacts on the right side of the switch SC (1 and 2) to control the 95 simultaneous transmission of series of impulses or continuous impulses over outgoing lines with which the numerals 1 and 2 are associated at the right hand end of the figure. The line 47 also extends to a make contact 48 of the relay 100 SP which is the start pulsing relay. When the switches SC and SC (1 and 2) are in the position shown in Figs. 1 and 6 and the contact 48 is open no impulses will be sent out over the outgoing lines with which the numeral 1 and 105 the letter L are associated.

Minus on the line 46 is also extended across the contact *a* to the line 50 which extends to the normally open contact 48r on the relay SP and to the switch SCr and to a contact on the 110 right hand side of the switch SC (1 and 2). When these switches are in the normal position, as shown, no impulses can be sent out over the lines with which the numeral 2 and the letter L are associated.

115 If it is desired to send out a series of one to ten pulses over either of the lines 1 and 2 the appropriate dial 40 or 40r is adjusted accordingly. If it is assumed that a relay to be tested is connected to line 1 and that it is desired to 120 send a series of five impulses to this relay the dial 40 will be moved to the 5 position to bring the arm 41, Fig. 6, into contact with the stationary contact 5. The switch C is moved to close its upper contacts. The switch SC is then 125 moved to close the upper contact and the switch F is moved to close its upper contacts.

As the contact *b* closes and opens it sends 130 pulses over the line 47 which now continue across the upper contact of the switch SC to line 51 which is the energizing lead of the stepping magnet SM. As this magnet operates it steps the arm 42 from its home position to a blank position and opens the circuit from battery across the arm 42 and line 52 of the relay 135 SP which at its contact 48 connects the line 47 to the line 51 so that the stepping magnet SM will be operated each time an impulse is sent over the contact *b* as long as the relay SP remains deenergized.

140 As pulses are sent out over the contact *b* minus on the line 46 is connected across one of the upper contacts of the switch C to line 53 and continues over the contact *d* to line 54 and from line 54 over the contact 55 of relay SP and a 145 break contact 56 of relay S to line 57 which is connected across one of the upper contacts of the switch F to the line 1. As the second pulse goes out over the contact *b* to step the arm 42 from the blank position to the one posi- 150

tion a pulse over the contact *d* goes out over the line 1 to energize a relay to be tested.

As the third pulse goes out over the contact *b* to operate the arm 42 a second pulse goes out over the contact *d* and the line 1 to operate the relay to be tested. This operation continues until the arm 42 is stepped on to the contact 5 at which position it completes a circuit from battery across the contact 5, arm 41 and the coil of relay *S*. As this relay picks up it disconnects the line 54 from the line 57 which is connected across the switch *F* to the line 1 and thus discontinues pulsing over the line 1 to the relay. Five pulses have now been sent out to the relay and further closing of the contact *d* will be an idle operation. The pulses over the contact *b* continue to go out over the line 47 and over the contact 48 and line 51 to the stepping magnet *SM* causing the arm 42 to continue the stepping movement. It is assumed that the switch *SC* was brought back to normal after the first operation of the stepping magnet. The stepping magnet will continue this operation until the arm 42 is moved over the ten contacts and the blank contact to the home position shown in Fig. 6, in which position battery is connected across the arm 42 to line 52 and across the coil of the relay *SP* to ground causing this relay to pick up and disconnect the line 47 at its contact 48 from the line 51 thus preventing further energization of the stepping magnet *SM* as the contact *b* closes and opens.

By means of the circuits described a series of five pulses have been sent out over the line 1 under control of the dial 40 and the parts have been restored to the position shown in Fig. 6.

As the relay *S* picked up during this operation it closed a holding circuit for itself from battery over the operated make contact 60 of the relay *SP* and its own make contact 61 so that this relay remained energized as the arm 42 was moved off contact 5 and remained energized until its holding circuit was broken by opening of the contact 60 upon energization of the relay *SP*, as the arm 42 moved into its home position. As the relay *SP* is energized it also opens the pulsing circuit for the line 1 at its contact 55.

If it is desired to send out successive series of any given number of pulses, for example 5 pulses in a series, the switch *SC* is moved as before to close its upper contacts and is left in that position. The mechanism will operate as before and the circuit will be made for the stepping magnet each time the contact *b* is closed so that energization and deenergization of the relay *SP* will have no effect on the operation of the stepping magnet *SM*. The arm 42 will be operated as before and as it moves from contact *B* to 1, 2, 3, 4 and 5 a series of five impulses will be sent out over the line 1, the transmission of impulses ceasing as the arm 42 moves over the contact 5 thereby causing energization of the relay *S* which opens the outgoing circuit at its contact 56. The arm 42 continues its movement into the home position but as its circuit is still closed over the upper contact of the switch *SC* it will continue its movement and make another rotation, the relay *SP* closing the pulsing circuit at its contact 55 to start pulses for the line 1 and the relay *S*, later opening the pulsing circuit at its contact 56 to stop the transmission of pulses over the line 1 after five pulses have been sent out. This operation will continue as long as the switch *SC* is in this position. By means of this mechanism spaced series of pulses may be

sent out over the line 1 under control of the dial 40 and the switch *SC*. As is obvious, each series may contain from one to ten pulses the number of spaces between the series of pulses being equal to 13—the number of pulses sent.

If it is desired to send continuous pulses over the line 1 the switch *SC* will be moved to close the lower contact to connect the line 54 directly to the line 57. In this case the stepping magnet *SM* will not be energized and the relay *SP* will remain energized so that the pulses will continue as long as the switch *SC* remains in this operated position.

If it is desired to send pulses out on the line 2 to a relay to be tested the dial 40r is set over the numeral designating the number of pulses desired and the switch *SCr* is moved to close its upper contact. As the contact *a* closes it extends minus on line 46 over line 50 and the upper contact of the switch *SCr* to line 62 and the coil of the stepping magnet *SMr* to ground causing this magnet to step the arm 42r clockwise to the blank position which opens the circuit for the relay *SPr* which at its contact 48r connects the line 50 to the line 62 so that the stepping magnet *SMr* will be energized in the event that the switch *SCr* has been brought back to normal position, as long as the relay *SPr* remains deenergized.

If it is desired to send a series of five impulses out over line 2 the dial 40r will be moved over the number 5 so as to position the arm 41r over the contact 5.

The switch *C* connected minus on the line 46 from the 48 volt battery over one of its upper contacts to line 63. The minus on line 63 is extended across the contact *c* to the line 64 which is connected across the contact 55r of relay *SPr* and the contact 56r of relay *Sr* to line 65 which is extended across one of the upper contacts of the switch *F* to the line 2.

As the arm 42r is moved from the home position to the blank position it causes the relay *SPr* to be deenergized and to prepare a pulsing circuit to the line 2 at its contact 55r. When the stepping magnet is operated again to move the arm 42r from the blank position to the one position a pulse is sent out over the contact, *c*, line 64, line 65 and line 2 to the relay to be tested. This operation continues until the arm 42r moves over the contact 5 which completes the circuit for the relay *Sr* which operates and opens the pulsing circuit at its contact 56r. The relay *Sr* at its contact 61r closes a holding circuit for itself over a contact 60r of relay *SPr* so that the pulsing circuit will remain open as long as the relay *SPr* remains energized, that is, until the arm 42r has made a complete rotation into the position shown in Fig. 6.

If it is desired to send a succession of series of pulses over the line 2 the switch *SCr* will be left in its operated position in which it connects the line 50 to the line 62.

If it is desired to send continuous pulses over the line 2 the switch *SCr* will be moved to close its lower contact to connect the line 64 directly to the line 65 so that the pulses over the line 2 will not be dependent upon the operation of the relays *SPr* and *Sr*.

It is obvious, of course, that by adjusting the dials 40 and 40r and by setting the switches *SC* and *SCr* a single series of pulses or a succession of series of pulses or continuous pulses will be sent out over the lines 1 and 2 simultaneously. It is obvious, of course, that the number of

pulses sent out over the line 1 may be different from the number of pulses sent out over the line 2 so that two relays may be tested simultaneously under different conditions.

- 5 For the purpose of sending out series of pulses or continuous pulses over both lines 1 and 2 a switch SC (1 and 2) may be provided. When this switch is moved so as to close the left hand contacts it will connect the line 54 to the line 10 57 and the line 64 to the line 65 thus causing continuous impulses to go out over lines 1 and 2.

When the switch SC (1 and 2) is moved so as to close the right hand contacts it connects the line 47 to 51 and the line 50 to the line 62

- 15 so that the impulses produced by the contacts b and a will cause the stepping magnets SM and SM_r to operate. If the dials 40 and 40_r have been set, for example to 4 and 6 respectively, a series of four impulses will go out over the line 20 1 and a series of six impulses will go out over the line 2 and but one series of impulses will go out over these lines if the switch SC (1 and 2) is moved back to normal position before the respective number of impulses have been sent out.

- 25 If the switch is left in this operated position successive series of four impulses will go out over the line 1 and a successive series of six impulses will go out over the line 2 and this will continue until the switch SC (1 and 2) has been

- 30 moved back into its home position.

If it is desired to send impulses from the 150 volt battery the switch C is moved so as to close the lower contacts and apply positive battery to the line 53 and negative battery to the line 63 so that positive impulses of 150 volts may be sent out over the line 1 under control of the left hand dial mechanism 40 and negative impulses of 150 volts may be sent out over the line 2 under control of the right hand dial 40_r.

If it is desired to test a polarized relay, positive and negative impulses may be sent to this relay over the line L when the switch F is moved so as to close its lower contacts and connect the lines 57 and 65 to the line L.

If it is desired to measure the length of a pulse going out to a relay to be tested and the control over the pulses is set up in the mechanism on the left by means of the dial 40 and switch SC, then 50 the clip 38, Fig. 6, is connected to the far side of the switch d, for example to the standard 15 on the right hand side of Fig. 5. Each time that a pulse is sent out over the line 54 a pulse will continue over the clip 38, the neon intensity control resistance NI, the primary coil P, over line 70, switch E, which now has been moved to close its upper contacts, and arm 71 to the positive side of the 48 volt battery, if the arm is positioned over the second contact in Fig. 6. As the 60 pulse builds up it induces a current in the secondary coil S, which operates the neon light 26, Figs. 6 and 3. This causes a flash to be observed through a slit in the disk 19, Figs. 1 and 9. As the pulse ceases it causes another flash of 65 the neon light 26 observable through the slit in the disk 19. By means of this mechanism the neon light is energized at the beginning and end of the pulse so that the length of the pulse can be measured in terms of 100%, by observing where these flashes occur, and reading or calculating the difference in percentage. The arm 71 is moved over the proper positive or negative contact to complete the circuit through the neon tube, as is understood.

75 In order to determine which of the flashes

represents the beginning of the pulse the switch E, Fig. 6, is moved to close its lower contacts so that the circuit over the coil P will continue over a contact 72 operated by this coil and over the switch E and arm 71 to the respective contact, etc. As the pulse passes over coil P it causes the contact 72 to vibrate which causes the neon light 26 to turn off and on in rapid succession. The effect of this observed from the front of the machine is a succession of lines following the first line of light produced through the slit at the beginning of the pulse or at make time of a relay to be tested.

By means of the adjustable contacts 14, Fig. 5, it is possible to shorten the length of the pulses until they are too short to operate the relay and to measure the length of such pulses. It is also possible to adjust the pulse to a length long enough to make the relay fail and to read or calculate the length of this pulse. By taking the mean between the length of the short and long pulses a satisfactory operating pulse for the relay may be calculated. The screws 14 will be adjusted until the flashes of the neon light in connection with the graduated scale 21 indicate that the pulse delivered to the relay is of the length determined by the above calculation.

If it is desired to find the length of time required for a relay to operate and to release for a given length pulse the relay will be operated and the disk 21 will be moved until the zero position is opposite the flash which indicates the beginning of a pulse. The clip 38, Figs. 6 and 11, is then shifted from the post 1, Fig. 11, to which it was clipped to measure the length of the pulses, to post 2 so that the neon light will be controlled by a circuit from battery over the contact 74 of relay R to be tested. When the contact 74 is closed the neon light 26 will flash and by rotating the member on the graduated ring 21 opposite the flash the length of time required to close the contact may be calculated directly. Each time that the contact 74 is opened the neon light will again flash and by observing the point on the scale opposite this flash the time of release of the relay may be calculated.

By referring to Fig. 7 it may be seen that the length of the pulse may be indicated by the inner partial circle bearing the legend "Generation" and the point at which the contact closes and opens may be indicated by the second circle from the center bearing the legend "Relay 1 Contact", and that the time required to close a contact may be directly read or calculated from this chart which, as shown, is 5% in the assumed case, and the time for release of the relay is 20% in the assumed case. The relay tested may operate another relay the operation of which may be represented by the third circle bearing the legend Relay 2 (Operated from Relay 1). It may then be calculated as to how long it took the relay 2 to pick up after the relay 1 picked up and after the pulse was completed, and how long it took the relay 2 to release after the first relay released and after the pulse ceased.

For certain testing operations it is desirable to have the neon light flash but once for each pulse sent out to the relay to be tested. For this purpose I have provided contacts 34 and 35, Figs. 2, 3 and 4, which apply a plus from a 2 to 6 volt battery to the transformer as indicated in Fig. 12, the secondary coil of which may be connected by a switch arm 75 to a neon tube associated with the dial mechanism such as shown in the

preceding figures or to an observation neon tube 76 or to the neon tube 77 in the oscillograph, see also Fig. 10. As the pulses are sent out to the relay to be tested the contacts 34 and 35 are closed but the voltage is insufficient to cause the neon tube to flash at the beginning of the pulse. As the contacts 34 and 35 remain closed for a certain length of time a sufficient amount of current will build up to cause the neon tube to 10 flash when these contacts are opened. By means of this mechanism one flash will be produced for every impulse sent out.

By turning the hand wheel 33, Fig. 1, the worm wheel 30 and contacts 34 and 35 may be rotated 15 so that this flash will occur at different times with respect to the outgoing pulse. If the arm 75, Fig. 12, is moved over contact 2 to energize the observation neon tube, which is preferably portable and may be caused to flash on the contact 20 74 of the relay R, Fig. 11, it will be noticed that by moving the contacts 34 and 35 that the neon tube may be caused to flash at any point of the contact 74 in any of its positions causing this contact to appear to be at rest in such 25 position. By means of this construction a still view of the contact may be had in any of its positions and its operation may be observed. After a still view of the contact or armature at any particular point of its movements has been observed 30 the switch arm 75, Fig. 12, may be moved over contact 1 or 3 to energize the neon tube 26 or 77, Fig. 12, which causes a flash to be made at the time that the contact reaches the particular position observed. The flash strikes the time 35 mirror 78 of an oscillograph and is reflected on a screen on which appears a curve indicating the pulse transmitted to the relay, such curve being made by the usual time mirror before referred to and an amplitude mirror 79 whose position 40 is controlled by the outgoing pulse, as is well understood. By means of this connection a vertical line will cross the graph of the pulse curve, Fig. 8, at a point corresponding to the part of the pulse corresponding in time to the 45 position of the contact 74 observed in the still view. This at once gives a visual relation between the beginning of a pulse and the position of the contact 74.

In Fig. 12 is shown an indicator unit such as 50 is used in well known teleregister systems which comprises an operating magnet 80 which cooperates with an armature 81 integral with an operating fork 82 which cooperates with a ratchet disk 83 on an indicator drum 84, the fork being 55 operated downwardly upon energization of the magnet and being pulled upwardly by a spring 85. Secured to the end of the indicating drum is a ratchet disk 86 provided with twenty-two holes, that is, twice the number of the positions 60 of the indicator with which cooperates a spring retaining finger 87. The magnet of the indicator unit may be connected to terminal 1, Fig. 6, and the length of the pulse which may be 48 or 150 volts, etc. may be adjusted until a maximum and minimum operating pulse is determined 65 after which the pulse may be adjusted to the best operating length. If it is desired to observe the operation of any part of this mechanism, for example, the fork, the observation 70 neon light 76, Fig. 12, is caused to flash on the operating fork at the desired time by the adjustment of the contacts 34 and 35, Figs. 3 and 4. After a still view is obtained of the fork or any part of the fork at the desired point of operation the arm 75, Fig. 2, is moved over contact 75 1 or 3 and the time relation between the point at which this observation is made and the beginning of the pulse may be observed on the oscillograph in Figs. 8 and 10. If desired, the neon tube associated with the dial construction in Figs. 1, 2 and 3 may be energized by moving the arm 75 over the contact 1, Fig. 12, and the position of the flash may be read on the graduated member 21, Fig. 3, and noted on the chart in Fig. 7 from which the exact time between the starting of the pulse and the time at which the operation is observed may be calculated.

If desired, a slow motion picture of the fork may be obtained by closing the switch for the motor mo, Figs. 1 and 2, by means by which the contacts 34 and 35 may be revolved forwardly at a slow speed so as to cause the neon tube to flash on the fork at a slightly later time during each successive operation of the fork. This will cause the fork to appear to travel forwardly very slowly. By mechanism well known the direction of the rotation of the motor may be changed and a slow motion picture of the fork appearing to move in the reverse direction may be observed.

Continuous minus from the 48 volt battery may be applied to line 1, Fig. 6, by closing the switch B, operating the switch C to close its upper contacts, operating a switch DC to connect line 53 to 54 directly, operating the switch 105 SC to connect the line 54 to 57, and operating switch F to connect line 57 to the line 1. Similarly, by operating switch DCr and operating switch SCR to connect line 63 to 64 and line 64 to 65, minus from battery may be applied to 110 line 2.

By operating switch C to close its lower contacts, plus from the 150 volt battery may be applied to line 1 and minus from battery may be applied to line 2.

By operating the switch F to close its lower contacts, single series of pulses, spaced series of pulses, continuous pulses, and direct current from either battery may be applied to line L for testing polarized relays.

As may be well understood, two neon tubes 26 may be employed, one of which may be operated from post 1, Fig. 11, and the other from post 2. Simultaneous operation of these tubes will cause a flash to appear at the beginning of a pulse, a second flash at the closing of contact 74, a third flash as the impulse ceases and a fourth flash as the contact 74 opens. In slow-to-release relays the complete time between the first and fourth flashes may be more than 100%. 130 In this event and for convenience in distinguishing generally between the various flashes, the additional tube 26 may be filled with a gas, such as mercury vapor, to emit a light of different color.

It is also to be noted that chattering of a contact either as it opens or closes may be observed by a series of flashes similar to those produced when the oscillating contact is used to produce a series of flashes to determine which of a pair 140 of flashes is produced at the beginning of a pulse.

It may also be found desirable to connect a condenser and resistance in parallel in the circuit of the neon tube, to produce a flash only 145 at the beginning of a pulse.

While the invention has been described with reference to a specific embodiment, it is obvious that various changes may be made without departing from the spirit of this invention and 150

that it is to be understood that the terms employed in the claims are terms of description rather than of limitation.

What I claim is:

- 5 1. The combination of an adjustable pulsing mechanism comprising a rotatable cam, means for rotating said cam at a constant speed, a movable circuit closing contact operable by said cam, an adjustable stationary contact cooperable 10 with said movable contact for controlling the length of a pulse, a slotted disk rotatable with said cam, a neon tube, means for operating said tube as the circuit is made and broken by said contacts, and a graduated circular scale associated with said disk. 15
2. The combination of an adjustable pulsing mechanism comprising a rotatable cam, a shaft supporting said cam, means for rotating said shaft at a constant speed, a movable circuit 20 closing contact operable by said cam, an adjustable stationary contact cooperable with said movable contact for controlling the length of a pulse, a slotted disk mounted fixedly on said shaft, a neon tube, means for operating said 25 tube as the circuit is made and broken through said contacts, and a graduated circular scale associated with said disk. 30
3. The combination of an adjustable pulsing mechanism comprising a rotatable cam, means for rotating said cam at a constant speed, a movable circuit closing contact operable by said cam, an adjustable stationary contact cooperable 35 with said movable contact for controlling the length of a pulse, a slotted disk rotatable with said cam, a neon tube, means for operating said tube as the circuit is made and broken by said contacts, a graduated circular scale associated 40 with said disk, and means for operating a relay to be tested by the circuit made through said contacts. 45
4. The combination of an adjustable pulsing mechanism comprising a rotatable cam, means for rotating said cam at a constant speed, a movable circuit closing contact operable by said cam, an adjustable stationary contact cooperable 50 with said movable contact for controlling the length of a pulse, means for connecting a relay to be tested in the circuit of said contacts, a second pair of contacts cooperating with said cam, means for adjusting said contacts circumferentially with respect to said cam, a neon tube, and means for operating said tube by the circuit 55 made across the latter pair of contacts as the circuit is broken. 60
5. The combination of an adjustable pulsing mechanism comprising a rotatable cam, means for rotating said cam at a constant speed, a movable circuit closing contact operable by said cam, an adjustable stationary contact cooperable 65 with said movable contact for controlling the length of a pulse, means for connecting a relay to be tested in the circuit of said contacts, a second pair of contacts cooperating with said cam, means for adjusting said contacts circumferentially with respect to said cam, a neon tube, means for operating said tube by the circuit 70 made across the latter pair of contacts as the circuit is broken, and manipulative means for adjusting said latter pair of contacts for obtaining a still view of the relay at any point of its movement. 75
6. The combination of an adjustable pulsing mechanism comprising a rotatable cam, means for rotating said cam at a constant speed, a movable circuit closing contact operable by said

cam, an adjustable stationary contact cooperable with said movable contact for controlling the length of a pulse, means for connecting a relay to be tested in the circuit of said contacts, a second pair of contacts cooperating with said cam, means for adjusting said contacts circumferentially with respect to said cam, a neon tube, and a motor for revolving said latter pair of contacts with the cam at any desired speed to obtain a slow motion view of the relay to be tested. 80

7. The combination of a mechanism for producing a desired constant number of pulses to operate a relay to be tested, means for controlling the transmission of a single series of a variable number of pulses, means for controlling the transmission of an indefinite number of series of variable pulses, and means for controlling the transmission of a continuous series of pulses. 90

8. The combination of a mechanism for producing a desired constant number of pulses to operate a relay to be tested, two sets of means for controlling the transmission of a single series of a variable number of pulses, two sets of means for controlling the transmission of an indefinite number of series of variable pulses, two sets of means for controlling the transmission of a continuous series of pulses, said two sets of means permitting two relays to be tested simultaneously. 100

9. The combination of a mechanism for producing a desired constant number of pulses to operate a relay to be tested, two sets of means for controlling the transmission of a single series of a variable number of pulses, two sets of means for controlling the transmission of an indefinite number of series of variable pulses, two sets of means for controlling the transmission of a continuous series of pulses, said two sets of means permitting two relays to be tested simultaneously, a plurality of electrical sources of different voltage, a motor operated by one of said sources for operating said pulse producing mechanism, and means for connecting said pulse producing mechanism to either source. 110

10. The combination of a mechanism for producing a desired constant number of pulses to operate a relay to be tested, two sets of means for controlling the transmission of a single series of a variable number of pulses, two sets of means for controlling the transmission of an indefinite number of series of variable pulses, two sets of means for controlling the transmission of a continuous series of pulses, said two sets of means permitting two relays to be tested simultaneously, a plurality of electrical sources of different voltage, a motor operated by one of said sources for operating said pulse producing mechanism, means for connecting the same side of one of said sources to the pulse producing mechanism to send out pulses of the same polarity under control of said two sets of means, and means for connecting said other source to the pulsing mechanism to transmit pulses of different polarities. 130

11. The combination of a pulse producing mechanism, an oscillograph comprising the usual time mirror and amplitude mirror for producing on a screen a curve of a pulse, means for operating a relay to be tested by said pulse, a neon tube, a second pulse producing device operable in adjustable timed relation to said first pulse producing device for operating said neon tube at any point in the duration of said first pulse for 140

- producing a still view of the armature of the relay to be tested at any point of its movement, means for operating said neon tube as the energizing pulse ceases, a second neon tube, and 5 means for energizing said second neon tube by said second pulse to project a line of light against the time mirror to be reflected across said curve to obtain a visual relation between the time of the amplitude curve and the point 10 at which the armature is observed.
12. The combination of a rotatable pulsing cam, a slotted disk rotatable with the cam, a neon tube associated with said disk, means for operating said neon tube, a relay to be tested by the 15 pulse produced by said pulsing cam, a graduated dial associated with said slotted disk, and means for adjusting said dial to move the zero of the dial opposite the line produced by the neon tube and the disk denoting the beginning of the pulse.
- 20 13. The combination of a rotatable pulsing cam, a slotted disk rotatable with the cam, a neon tube associated with said disk, means for operating said neon tube, a relay to be tested by the pulse produced by said pulsing cam, a graduated 25 dial associated with said slotted disk, means for adjusting said dial to move the zero of the dial opposite the line produced by the neon tube and the disk denoting the beginning of the pulse, means for energizing said neon tube at the beginning and end of the pulse, and a vibrator for 30 causing said neon tube to flash a plurality of times during the continuation of the pulse for the purpose of determining which of the flashes indicates the beginning and the end of the pulse.
- 35 14. The combination of a lamp, pulsing mechanism for transmitting spaced pulses of different lengths across the circuit of said lamp, and means cooperating with said lamp for measuring the length of pulses transmitted.
- 40 15. The combination of a neon tube, pulsing mechanism for transmitting spaced pulses of different lengths over the circuit of said neon tube, means for causing said neon tube to light as the circuit is made and broken, and means 45 cooperating with said neon tube for measuring the length of said pulses.
16. The combination of a neon tube, pulsing mechanism for transmitting pulses of different lengths over the circuit of said neon tube, means 50 for causing said neon tube to light as the circuit is made and broken, a scale cooperating with said neon tube, and means for causing a light from said neon tube to light different parts of said scale to indicate by the intercepted portion 55 of said scale the length of the pulse over the circuit of said neon tube.
17. The combination of a lamp, pulsing mechanism for transmitting pulses of different lengths across the circuit of said lamp, means 60 cooperating with said lamp for measuring the length of pulses transmitted, and means causing a relay to be tested, to be operated by the pulses transmitted over said circuit.
18. The combination of mechanism for producing pulses of different lengths, means for 65 connecting a relay to be tested in a circuit over which said pulses are transmitted, means for transmitting pulses over a second circuit subsequently and in adjustable varied time relation to said first pulses, a neon tube in said 70 second circuit, and means for operating said neon tube at the termination of each of said second pulses.
19. The combination of mechanism for producing pulses of different lengths, means for 75 connecting a relay to be tested in a circuit over which said pulses are transmitted, means for transmitting pulses over a second circuit subsequently and in adjustable varied time relation to said first pulses, a lamp in said second circuit, and means for operating said lamp at the termination of each of said second pulses. 80
20. The combination of mechanism for transmitting pulses of variable lengths over the coil of a relay to be tested, and manipulative controlled means for controlling the automatic successive transmission of a continuous series of a variable number of pulses. 85
21. The combination of mechanism for transmitting pulses of variable lengths over the coil of a relay to be tested, and manipulative means for controlling the automatic successive transmission of a plurality of spaced series of pulses each containing a predetermined number of pulses. 90
22. The combination of mechanism for transmitting pulses of variable lengths over the coil of a relay to be tested, manipulative controlled means for controlling the automatic successive transmission of a continuous series of a variable 100 number of pulses, of one of a plurality of different voltages.
23. The combination of mechanism for transmitting pulses of variable lengths over the coil of a relay to be tested, manipulative controlled means for controlling the automatic successive transmission of a continuous series of a variable 105 number of pulses, of either polarity.
24. The combination of pulsing mechanism for transmitting pulses over the coil of a relay 110 to be tested, a neon tube, means for operating said neon tube at the beginning and end of a pulse, and a vibrator for causing said neon tube to flash a plurality of times during the continuation of the pulse. 115
25. The combination of means for transmitting pulses of variable lengths over the coil of a relay to be tested, means for measuring the length of said pulses, and means for measuring the operating time and release time of the relay. 120
26. The combination of means for transmitting pulses of variable lengths over the coil of a relay to be tested, and means for graphically indicating the value of the pulse at the time the relay is 125 fully operated.
27. The combination of means for transmitting pulses of variable lengths over the coil of a relay to be tested, means for obtaining a still view of the movable armature at any point of its movement, and means for graphically indicating the 130 point of the pulse at which the relay armature is observed.
28. The combination of means for transmitting pulses of variable lengths over the coil of a relay to be tested, means for obtaining a still view of the movable armature at any point of its movement, and means for indicating on a scale the point of the pulse at which the relay armature is 135 observed.
29. The combination of means for transmitting pulses over the coil of a relay to be tested, a neon tube connected in a circuit across the armature of said relay, and means for causing said neon tube to light momentarily as the armature closes the circuit to visually indicate chattering of the armature. 140
30. The combination of means for transmitting pulses over the coil of a relay to be tested, a neon tube connected in a circuit across the armature 145 of the relay, and means for causing said neon tube to light as the armature closes the circuit to visually indicate chattering of the armature. 150

tube to light to visually indicate chattering of the armature as the relay is energized and deenergized.

31. The combination of mechanism for transmitting pulses over the coil of a relay to be tested, signal means, and means for operating said signal means at the beginning of a pulse, at the time the armature of the relay closes, at the end of the pulse and at the time the armature of the relay opens.
32. The combination of mechanism for producing pulses, means for connecting a relay to be tested in a circuit over which said pulses are transmitted, means for transmitting pulses over a second circuit subsequently and in adjustable varied time relation to said first pulses, a lamp in said second circuit, and means for operating said lamp at the termination of each of said second pulses.
33. The combination of a lamp, pulsing mechanism for transmitting spaced pulses across the circuit of said lamp, and means cooperating with said lamp for measuring the length of pulses transmitted.
34. The combination of a neon tube, pulsing mechanism for transmitting spaced pulses over the circuit of said neon tube, means for causing said neon tube to light as the circuit is made and broken, and means cooperating with said neon tube for measuring the length of said pulses.
35. The combination of mechanism for transmitting pulses over the coil of a relay to be tested, and manipulative controlled means for controlling the automatic successive transmission of a continuous series of a variable number of pulses.

36. The combination of mechanism for trans-

mitting pulses over the coil of a relay to be tested, and manipulative means for controlling the automatic successive transmission of a plurality of spaced series of pulses each containing a predetermined number of pulses.

37. The combination of mechanism for transmitting pulses over the coil of a relay to be tested, manipulative controlled means for controlling the automatic successive transmission of a continuous series of a variable number of pulses, of one of a plurality of different voltages.
38. The combination of mechanism for transmitting pulses over the coil of a relay to be tested, manipulative controlled means for controlling the automatic successive transmission of a continuous series of a variable number of pulses, of either polarity.

39. The combination of means for transmitting pulses over the coil of a relay to be tested, and means for graphically indicating the value of the pulse at the time the relay is fully operated.

40. The combination of means for transmitting pulses over the coil of a relay to be tested, means for obtaining a still view of the movable armature at any point of its movement, and means for graphically indicating the point of the pulse at which the relay armature is observed.

41. The combination of means for transmitting pulses over the coil of a relay to be tested, means for obtaining a still view of the movable armature at any point of its movement, and means for indicating on a scale the point of the pulse at which the relay armature is observed.
